COMB

William J. Mims, Birmingham, Ala.

Application September 20, 1945, Serial No. 617,496

2 Claims. (Cl. 132—16)

1

This invention relates to a comb of that type adapted to be heated when in use and has for an object the provision of a device of the character designated which shall include separable teeth and a detachable handle and wherein the comb may be easily assembled and disassembled and the handle removed and replaced during the cleaning operation.

A further object of my invention is to provide a comb adapted to be heated when used and which shall include a handle which does not become overheated when heating the comb.

Combs which include teeth adapted for separation in cleaning are well known in the art as are combs which are adapted to be heated when in use. Difficulties have been found in the use of such combs in that the handle, if made of metal, is liable to become overheated when heating the comb so that it may not be handled in comfort and, if made of wood, is liable to catch fire and become charred when heating the comb.

These and other difficulties are overcome in accordance with my invention in which I provide a comb with separable teeth mounted on a suitable rod with spacers between the teeth. Adjacent the teeth, I provide an elongated cuff which fits over the mounting rod and which bears at its end remote from the teeth against a wood handle having a bore substantially larger than the diameter of the mounting rod. The outer end of the mounting rod is provided with a threaded section and the outer end of the handle is provided with an internally threaded sleeve which is mounted wholly within the handle and is adapted to screw onto the threaded section of the mounting rod and by means of which the cuff may be brought to bear snugly against the teeth and spacers to hold them rigidly in position for use. By the means employed, heat from the comb is not readily transmitted to the handle and it does not become charred or burned and may be handled at all times with comfort.

A device embodying features of my invention is illustrated in the accompanying drawing, forming a part of this application, in which

Fig. 1 is a sectional elevation of the comb; and
Fig. 2 is a sectional view taken along the line II—II of Fig. 1.

Referring to the drawing for a better understanding of my invention, my improved comb comprises a mounting rod 10 which may be of any suitable angular cross section, preferably of an X section as shown in Fig. 2 of the drawing. On one end of the mounting rod 10 is provided a permanently affixed head 11. The other end of the

2

mounting rod is provided with a threaded section 12 having a pointed outer end 13. Mounted on the rod 10 and abutting the head 11 is a row of metal teeth 14 which have openings therein of a shape to fit snugly over the mounting rod 10. Between the teeth 14 on the rod 10 are suitable spacers 16, also made of metal and which hold the teeth 14 in properly spaced relation on the mounting rod.

10 Abutting the row of teeth 14 on the end opposite the head 11 is an elongated cuff 17 which fits over the mounting rod 10. The cuff 17 is provided with a shoulder 18 which bears against the end of a handle 19. While other materials may be employed, I prefer at present to employ wood for the handle 19 for the reason that it is a poor conductor of heat and I have found it better than most other available materials in service. The handle 19 is provided with a central bore 21 which, as may be seen in the drawing, is substantially larger in diameter than the mounting rod 10 so that the walls of the bore are spaced from the mounting rod when the handle is placed thereon. There is thus provided a substantial dead air space surrounding the handle. Adjacent the cuff 17, the handle is provided with a counter bore 22 bearing against the end of the cuff 17.

20 Mounted within the outer end of the handle 19 is an internally threaded sleeve 23 which is held in place in the handle by a drive fit and by means of fins 24, which engage the handle as it is driven into place. The sleeve 23 is adapted to screw onto the threaded section 12 of the mounting rod, as shown in Fig. 1. It is hollowed out as shown at 26 on its inner end, whereby when assembling 25 the comb after it has been taken apart, the pointed end 13 of the threaded section 12 engages the hollowed-out, funnel-like portion 26 of the sleeve 23 and enters the section 12 into the sleeve. The 30 comb is thus readily assembled after being taken apart.

35 From the foregoing, it will be apparent that I have devised an improved metal comb adapted to be heated when used and be taken apart for cleaning, which is simple of construction, easy of assembly and disassembly, and which includes a handle which will not become overheated when the comb is in use.

40 While I have shown my invention in but one form, it will be obvious to those skilled in the art that it is not so limited, but is susceptible of various changes and modifications, without departing from the spirit thereof, and I desire, 45 therefore, that only such limitations shall be

placed thereupon as are specifically set forth in the appended claims.

What I claim is:

1. In a comb embodying separable metal teeth and spacers between the teeth all mounted upon a mounting rod, a head on the outer end of the mounting rod against which the row of teeth bear, an elongated cuff mounted on the mounting rod at the other end of the row of teeth and bearing thereagainst, a wooden handle mounted on the mounting rod and having a bore substantially larger in diameter than the rod throughout its length to form therewith a substantial dead air space and bearing at one end against the cuff, a threaded section on the outer end of the mounting rod, and an internally threaded sleeve mounted in the outer end of the bore of the handle and adapted to screw onto the threaded section. 15

2. In a comb embodying a row of metal teeth with spacers between the teeth, all slidably mounted on a mounting rod, a head on the rod at the outer end of the row of teeth against which the row of teeth bear, an elongated cuff slidably

5 mounted on the rod and bearing against the inner end of the row of teeth, a wooden handle on the rod bearing against the cuff and having a bore therein substantially larger in diameter than the rod and forming therewith a substantial dead air space, a threaded pointed outer end on the mounting rod, and an internally threaded sleeve mounted within the outer end of the handle and covered thereby, said sleeve having its end inside the handle funnel shaped whereby to receive the pointed end of the mounting rod.
